UNITED STATES PATENT OFFICE.

HERBERT J. GWYER, OF YONKERS, NEW YORK.

REFRIGERATOR CONSTRUCTION.

1,328,324.

Specification of Letters Patent. Patented Jan. 20, 1920.

Application filed June 10, 1919. Serial No. 303,197.

To all whom it may concern:

Be it known that I, HERBERT J. Gwyer, a citizen of the United States of America, residing at Yonkers, New York, have invented a new and useful Refrigerator Construction, of which the following is a specification.

My present invention relates to refrigerators, ice boxes and the like, and the objects of the invention are to provide a practical, serviceable cabinet construction of this character which can be made up in "knocked-down" form and of standardized parts, which parts can be shipped or stored in compact form and can be readily assembled when desired.

Another object is to so construct the parts that in the act of assemblage, the parts will be automatically drawn together into close fitting engagement and thus form an efficient "tight" box.

These various objects I have accomplished by constructing a box with top and bottom panels or sections and interfitting corner posts and side sections engaged between the top and bottom panels, said parts being so constructed and related that upon the drawing of the top and bottom panels together, the parts will all be compressed into tight fitting engagement. The lining may be made in parts or sections corresponding to the sections of the box and such lining sections are arranged also to be brought into close fitting engagement by the securing of the box sections.

Other features of the invention and details of construction will appear as the specification proceeds.

In the accompanying drawings I have disclosed the invention embodied in one of its practical commercial forms, but would have it understood that modifications may be made without departure from the true spirit and scope of the invention.

55 In said drawings:

Figure 1 is a perspective view of a refrigerator constructed in accordance with and embodying features of the invention.

Fig. 2 is a vertical sectional view of the same on a somewhat enlarged scale.

Fig. 3 is a horizontal sectional view on substantially the plane of the line 3—3 of Fig. 2.

Fig. 4 is a detached detail view of one of the supporting feet.

Figs. 5 and 6 are broken detail views of the front and back panels respectively.

Fig. 7 is a similar view of one of the side panels.

Figs. 8 and 9 are plan and sectional views respectively of the bottom panel.

Figs. 10 and 11 are similar views of the tray or lining for the bottom section.

Fig. 12 is a broken detail view of one of the corner posts.

Fig. 13 is a perspective view of the ice tray.

Figs. 14, 15, 16 and 17 are broken detail views of modified features of construction.

Referring now to the drawings in detail; 70 17 designates the top, 18 the bottom and 19, 20, 21 and 22 the four sides of the box. The panel sections 20 and 22 constitute what is ordinarily considered the front and the back of the box, but for the purposes of this disclosure the four sides will all be considered 75 simply as side panels, as practically the only difference between these several panels is in the matter of size and provision of the front panel with suitable doors such as indicated 80 at 23.

The corner posts are designated 24 and an interlocking or interfitting engagement is effected between these corner posts and the adjoining side panels by providing said 85 posts on the different angular sides thereof with groove-ways 25 to receive the edges of the side panels.

The top and bottom panels or framing pieces fit over the ends of the corner posts 90 and the side panels, being provided in the present disclosure with overfitting grooved portions 26 receiving the ends of the corner posts and the ends of the side panels. The engaging or meeting faces of the top and 95 bottom panels and the corner posts are preferably beveled or inclined somewhat, substantially as indicated at 27 in Fig. 14 so that as said top and bottom panels are drawn toward each other, the corner posts 100 will be forced inwardly and compressed upon the side panels. Similarly, the meeting faces of the top and bottom panels and adjacent ends of the side panels may be inclined or beveled as indicated at 28, so 105 that in addition to the compression of the corner posts on the side panels, the side panels will actually also be compressed by the top and bottom panels.

The top and bottom are drawn together in 110

the present illustration by means of tie bolts 29 extending preferably full length of the box between such panels. This tie bolt is shown more in detail in Fig. 14, a nut 30 being shown engaged on the lower threaded end thereof below the bottom panel. It will be evident that by means of these tie bolts the top and bottom panels are drawn together and as these panels exert a compressing effect upon the corner posts and side panels, tight joints will be effected and a closely sealed box will be secured by simply tightening these tie bolts.

The several panel sections are suitably constructed for the purpose to which the box is to be put, being ordinarily provided with suitable heat insulating material.

A lining is usually provided for the box, the same being here shown as sectional in character, corresponding to the sections of which the box is made. Thus, the side sections are shown as provided with a facing 31 forming a lining section, and the corner strips are shown provided with a lining material 32 covering the inside corner portion thereof, this latter lining section being held in place for instance, by turning the edges thereof into the grooves 25 provided for the side panels. The edges of the corner post lining preferably abut or engage the side panel lining sections when the parts are assembled, substantially as indicated in Fig. 3.

The bottom lining section consists in the illustration of a pan or tray 33 supported on the bottom panel and provided in the present disclosure with upturned angular flanges or lugs 34 at the corners thereof fitting up in recesses 35 provided behind the corner post lining sections. The top lining section similarly consists of an inverted tray member 36 which likewise may have angular flanges at the corners thereof to fit into recesses 37 provided at the back of the corner post lining sections (Fig. 12). The edges of these top and bottom lining trays may simply abut against the ends of the panel linings, as indicated at Fig. 2. By means of this construction, the trays are positively held in position and close joints are effected with the side panel and corner post sections of the lining.

As a possible modification, the lining sections may have extensions bent into the grooves provided in the top and bottom panels and in the corner posts, substantially as indicated at 38 and 39, in Figs. 15 and 16 respectively.

The box shown is provided with special supporting feet made in this case of sheet metal bent to form the angularly related side portions 40 connected at the top by a shelf portion 41, said shelf portion having upstanding positioning lugs 42 at the outer corners thereof beyond the edges of the an-

gular sides 40 for engagement with the side edges of the box. A further novel feature is the securing of these supporting feet in position by means of the same stay bolts which fasten the parts all together, said bolts extending through openings 43 provided in the shelf portions of these feet so that the act of securing the parts together also serves to fasten the supporting feet in position.

The box may be provided with the usual ice tray such as indicated at 44 and with a suitable drain pipe 45.

From the foregoing, it will be evident that by means of my invention the several parts of the refrigerator are all secured together in close fitting engagement by means of simple fastenings drawing the top and bottom panel together and which fastenings may, as described, be simply four tie bolts extending the full length of the box. These tie bolts are disposed in suitable grooves or holes 46 formed in the corner posts behind the lining and so are not exposed or in the way, (see Fig. 3).

The various parts of the refrigerator may be made up in bulk and stored or shipped in the knocked-down form, and said parts can, by reason of the novel construction disclosed, be quickly assembled when required without the need of any special tools, into a practical and efficient refrigerator.

The top and bottom lining sections may be provided with marginal flanges, as indicated at 47 in Fig. 14, to slide in back of the side and corner post lining sections to thus provide overlapping tight joints at these points.

In Fig. 17 I have illustrated how the corner post sections 48 may be made as a part of the side panel sections 49. This construction does away with the handling of the corner posts as separate units. In this I have illustrated how the corner post lining sections may be made as a part of the side lining sections, this combined side and corner post lining section being indicated at 50, and being shown as provided with flanged edges 51 overlapping and standing back of the lining section 52 of the adjoining side panels 53.

I claim:

1. In a cabinet construction, the combination of corner posts, side panels having interlocking engagement with said corner posts, top and bottom panels having connection with the corner posts to effect compression of the corner posts upon the side panels and tie bolts for drawing the top and bottom panels toward each other to thereby secure all of said parts in close fitting engagement.

2. In a cabinet construction, the combination of corner posts, side panels having interlocking engagement with said corner posts, top and bottom panels having connection with the corner posts to effect compression of the corner posts upon the side

panels, tie bolts for drawing the top and bottom panels toward each other to thereby secure all of said parts in close fitting engagement, and a sectional lining for said cabinet and held with the parts in close fitting engagement by the securing of the top and bottom panels as aforesaid.

3. In a cabinet construction, the combination of corner posts; side panels having interlocking engagement with said corner posts, top and bottom panels having connection with the corner posts to effect compression of the corner posts upon the side panels, tie bolts for drawing the top and bottom panels toward each other to thereby secure all of said parts in close fitting engagement, the means for effecting the compression of the corner posts upon the side panels comprising relatively inclined meeting faces on the ends of the corner posts and the top and bottom panels respectively.

4. In a cabinet construction, the combination of corner posts, side panels having interlocking engagement with said corner posts, top and bottom panels fitting over the ends of the corner posts and side panels, and arranged to compress said parts in close fitting engagement and means for securing the top and bottom panels in place.

5. In a cabinet construction, the combination of corner posts, side panels having interlocking engagement with said corner posts, top and bottom panels having connection with the corner posts to effect compression of the corner posts upon the side panels, tie bolts for drawing the top and bottom panels toward each other to thereby secure all of said parts in close fitting engagement, linings on the inner surfaces of

the corner posts and side panels and top and bottom lining sections held in engagement with said side panel and corner post lining sections by the securing of said parts as aforesaid.

6. In a cabinet construction, the combination of corner posts, side panels having interfitting engagement with said corner posts, a lining carried by said side panels and corner posts, a bottom panel engaged with the lower ends of the corner posts and side panels, a bottom pan supported by said bottom panel and having flanged portions engaged behind the lining aforesaid, a top panel and a top lining section completing the lining within the cabinet.

7. In a cabinet construction, the combination of corner posts, side panels having interfitting engagement with said corner posts, a lining carried by said side panels and corner posts, and provided with recesses behind the same at said corner posts, a bottom panel, a lining pan supported by said bottom panel and having upturned flanges at the corners thereof engaged in said recesses at the corner posts, a top panel and a top lining section completing the lining within the cabinet.

8. In a cabinet construction, the combination of corner posts, side panels having interlocking engagement with said corner posts, top and bottom framing pieces interengaged with the ends of the corner posts and side panels and arranged to hold said parts in close fitting engagement and means for drawing the top and bottom framing pieces into place.

HERBERT J. GWYER.
